VACUUM CONTAINER

Filed April 19, 1928

FIG. 2.

FIG. 3. BY G. J. Jefferson Langatt
ATTORNEY.

UNITED STATES PATENT OFFICE

AARON GREENLEAF CLOUGH, OF AYER'S CLIFF, QUEBEC, CANADA

VACUUM CONTAINER

Application filed April 19, 1928. Serial No. 271,202.

The invention relates to a vacuum container, as described in the present specification and illustrated in the accompanying drawings that form part of the same.

5 The invention consists essentially of the novel features of construction pointed out broadly and specifically in the claim for novelty following a description containing an explanation in detail of an acceptable 10 form of the invention.

The objects of the invention are to eliminate the necessity of ice packings in the transportation of ice-cream, milk, cream and other foodstuffs requiring cold or hot storage during the passage; to reduce the weight and consequently facilitate the handling of packages forwarded from urban centers to suburban and country districts or foodstuffs from the country to the cities, and 15

thus insure despatch for ice-cream or such commodities in the summer time; to afford to country residents comfort, ease and luxury, notwithstanding that they may be some distance from their city homes, as by means 20

25 of these containers all kinds of foodstuffs can readily be sent to merchants in the different centers without requiring the use of ice, and furthermore many of the products of the country can readily be packed in 30 these containers and forwarded, no matter what the weather conditions may be and yet retain their sweetness and purity free from contamination; to utilize a well known principle in a new construction, whereby simplicity is assured and the protection of the foodstuff guaranteed through the adoption 35 of common practice for the preservation of the contents; to produce a container that will be well within the reach of every shipper, in so far as the cost of the same is concerned, and which will withstand rough 40 handling without affecting its preservative qualities; and generally to provide a durable and efficient vacuum container.

45 In the drawings, Figure 1 is a vertical sectional view of the container, showing the arrangement of the parts in respect to the vacuum jacket.

50 Figure 2 is a side elevational view of the container complete.

Figure 3 is a cross sectional view of the container on the line 3—3 in Figure 2.

Like numerals of reference indicate corresponding parts in the various figures.

Referring to the drawings, the numeral 55 10 indicates the outer metal casing of considerable size, preferably cylindrical in shape, and converging by means of the tapered shoulder 11 to the neck 12.

The numeral 13 indicates the inner metal 60 casing, spaced from the outer metal casing 10 to form the vacuum chamber 14, completely around the wall and bottom of the can.

The inner metal casing 13 converges at 65 the shoulder 15 to the neck 16 and is joined to the outer casing 10 at the upper end by the bevelled top 17 closing in the vacuum chamber 14.

The inner metal casing 13 is supported at 70 its lower end on the flanged ring 18, having the elongated slots 19 therethrough, in order that there may be no interruption to the withdrawal of the air from the chamber 14.

The ring 18 is rigidly secured so as to 75 maintain the inner metal casing 13 in the central position within the outer casing 10.

The air is withdrawn from the chamber 14 through the outlet 20, closed by the plug 21, this outlet being preferably through the 80 bottom of the outer casing 10.

The annular gasket 22 of cork or other resilient material is secured on the bevelled top 17, so that it projects above the extreme upper end of the outer metal casing 10, 85 and this gasket 22 is compressed by the container cover 23.

The cover 23 has the bottom 24, the top 25 and the intermediate wall 27 forming the dead air space 26 and the vacuum chamber 90 28 and from the bottom 24 the flange extends downwardly to fit in the neck 16 of the vessel, this flange being bevelled at 29 to meet the gasket 22, the straight or vertical portion of the flange beginning at 30 95 slightly above the straight portion of the neck 16.

The bottom 24 of the cover is curved 100 downwardly forming a rim beyond the walls of the vessel and engages the top of

the outer wall, thus in clamping the cover to place, as explained hereinafter the downwardly curved rim portion pushes inwardly on the outer wall, while the horizontal portion of the bottom and the bevelled portion of the flange press downwardly on the gasket 22 and thus the two walls at the top are brought closely together to form an air tight joint.

10 The fasteners 33 are arranged one on either side, and each comprises a pivot plate 34 secured to the cover at either side, and a loop 35 pivotally secured to said plate, and a hasp 36 carrying a hook 37 and fitting over a staple 38, one on either side of the container, said hasp 36 being secured to said staple by the pin 39 or any suitable locking device, such as a padlock.

15 In this fastener device, the lever or arm 36 is pivotally secured at either side, by the pin 40, from the plate 41, there being such a plate at either side of the container.

20 The end of each hasp forms a barrel 42 for the pin 40, while the hasp 36 carrying the hook 37 acts as a lever in securing the closure, consequently when the hasps are loose the hooks may be inserted in the loops 35 and by effecting a downward pull the cover is fitted closely into the neck and the 25 hasp closed inwardly on the staples. The hasp is then fastened by pins or by a padlock if desired, thus securely closing in the 30 contents of the vessel within a vacuum jacket.

35 The outer casing 10 is lagged by the wooden jacket 45, which forms the dead air space 46, completely surrounding the casing 10 up to the top of the neck 12, this spacing being done by the several spacers 40 47.

45 The wall of the wooden jacket extends below the bottom 48 of the outer casing and is rigidly secured to the base ring 49, which in turn is held to a spacer 47, and lower extension 50 of the wall of the casing 10, and to the angle ring 51 by the rivets 52.

50 Thus a very substantial annular base is provided for the container and above said angle ring the wooden bottom 53 closes in a metal bottom 48 and is securely held by 55 said angle ring 51.

55 The cover 23 is closed in at the upper end by the wooden sheathing 54, secured by the angles 55 for lagging said cover, in addition to the deadening of the same by the air space 26.

60 It will be thus seen that a container is provided which is completely deadened or lagged, and at the same time surrounded by a vacuum, therefore when it is securely sealed there is no chance of the outside air reaching the foodstuffs contained therein, and if these foodstuffs happen to be of the ice-cream variety the temperature of that 65 commodity will not change, no matter how

long the journey may be, and it is only by opening it to the air that there will be any trouble in that respect. In the same way warm concoctions, such as tea, coffee, cocoa and various beverages may be kept in the 70 warm state that they were packed, without the temperature of the same being in any way reduced during the passage. Similarly meats and other foodstuffs may be sent to 75 country places and kept in good condition, which is a very important thing, as there are many residents that are not within easy reach of the iceman.

Consequently, the uses of this invention 80 are manifold, especially in the increasing communications between the city and the country in so far as merchandising is concerned.

What I claim as my invention is:—

A container comprising a double walled 85 and bottomed vessel having an air outlet for exhausting the air to form a vacuum jacket between the inner wall flared in a bevel surface at the upper end and an outer wall meeting said bevelled end, a plug closing said outlet, a flanged ring supporting the inner bottom and having slots in the ring wall forming ports in the withdrawal 90 of the air, a gasket on said bevel surface and a cover having a vacuum chamber and a bevelled lower portion engaging the aforesaid bevel surface and a downwardly turned rim portion engaging the outer wall and co-operating with said lower portion in sealing 95 the vacuum jacket after the cover has been clamped into its closed position.

Signed at Montreal, Canada, this 30th day of March, 1928.

AARON GREENLEAF CLOUGH.
